A. A. MILLER

PAPER SUPPLY HOLDER FOR TYPEWRITERS

Filed Sept. 3, 1924

Fig. 5. *Arthur A. Miller,* Inventor

By *Clarissa A. O'Brien.*

Attorney

UNITED STATES PATENT OFFICE.

ARTHUR A. MILLER, OF SELINSGROVE, PENNSYLVANIA.

PAPER-SUPPLY HOLDER FOR TYPEWRITERS.

Application filed September 3, 1924. Serial No. 735,635.

To all whom it may concern:

Be it known that I, ARTHUR A. MILLER, a citizen of the United States, residing at Selinsgrove, in the county of Snyder and

5 State of Pennsylvania, have invented certain new and useful Improvements in Paper-Supply Holders for Typewriters, of which the following is a specification.

This invention relates generally to typewriters and has more specific reference to a 10 device adapted to be disposed at the rear of a typewriter for holding a supply of paper for use, during the operation of the typewriter.

15 In carrying out the invention, it is necessary to provide a supply of paper, in the form of a tablet, the sheets of which are folded upon a backing and joined to each other through a fold line, which is perforated in order that the different sheets may

20 be severed from each other when necessary. A further object of the invention is to provide a supply holder of this character, that is so constructed as to hold what is 25 known as first and seconds as well as a tablet of carbon paper that is to be arranged between said first and seconds, for providing the usual original and carbon copy of the matter being typed.

30 An additional object is to provide a holder of this character to be employed with paper in tablet form, whereby it will not be necessary to manually place new sheets within the typewriter at the completion of 35 other sheets.

A further and important object is to provide means for catching the paper after the matter has been written and for allowing the paper to again return to its folded form, 40 in order that the different letters or the like may be severed from each other.

With the foregoing and other objects in view, as the nature of the invention will be better understood, the same comprises the 45 novel form, combination, and arrangement of parts hereinafter more fully described, shown in the accompanying drawing, and claimed.

In the drawing, wherein like reference 50 characters indicate corresponding parts throughout the different views:

Figure 1 is a central vertical section taken approximately upon the line 1—1 of Figure 2.

55 Figure 2 is a front elevational view thereof.

Figure 3 is a fragmentary edge elevational view showing a pair of intermeshing spur gears that are carried at the adjacent ends of a pair of feed rollers disposed forwardly of a paper receiving basket that forms an important part of the present invention.

Figure 4 is an edge elevational view of the form of continuous sheet tablet that is 60 adapted to be employed in the use of a typewriter attachment of this character, and

Figure 5 is a plan view showing certain sheets of the table interconnected through 65 perforated fold lines.

Now having particular reference to the drawing, 5 designates the typewriter that includes among other elements the platen 6. My invention per se constitutes the provision of the paper supporting frame, which 70 includes spaced vertical legs 7—7 that are preferably formed from strips of sheet metal, the lower end thereof being twisted and bent at right angles to provide supporting feet 8, that are bolted or otherwise suitably secured to the desk or other support for the typewriter, and at a point directly 75 back of the typewriter, as clearly shown in Figure 1.

Secured at their inner ends to the legs 80 7—7 of the frame, and adjacent the opposite ends of the leg are rearwardly extending spaced pairs of upper and lower horizontal bars 17 and 18 respectively. Upon opposed faces of the lowermost bars 18, there is 85 formed what may be called cups 9, while formed on the opposed faces of the uppermost bars and in vertical alignment with said cups are spaced guides 10. Each cup is 90 in reality composed of a comparatively small angle bracket and a cooperating ear disposed in spaced relation above the end 95 of the horizontal portion of the bracket. The construction is plainly shown in Figure 100 1. There are preferably three sets of cups and guides. Disposed within complementary sets of guides and cups are the backings A of tablets B, C and D. One of these tablets, specifically the one designated D, is for the original letter, the intermediate 105 tablet C is for the carbon paper, and the remaining tablet B for the carbon copy of the letter.

Each of the tablets employed is of the form shown in Figure 4, comprising as above stated, a backing A, to which is secured at one edge, one edge of the innermost sheet of a plurality of joined sheets E that 110

assume a folded position upon the backing, and that are secured to each other through perforated fold lines F, in order that the sheet may be readily severed whenever 5 necessary.

Forwardly of the guides 10 of the frame are lugs 11 that prevent the entire unfolding of the pads when the same are positioned in the frame, as shown in Figure 1.

10 Disposed above the opposed guides 10 and extending between the vertical legs 7 are two pairs of rods 19 between which the sheets are adapted to be trained in order to bring them into superposed relation before 15 they pass around the platen 6.

It will be obvious that in the use of the typewriter 5, the sheets of the three pads are passed in superposed relation about a typewriter platen 6, and that as the platen 20 is rotated, the sheets will be pulled from the pads, for allowing numerous letters to be written without applying individual sheets before starting each letter.

Pivottally secured to the upper ends of the 25 legs 7—7 is a sheet receiving basket 12, that may be swung to the dotted line position shown in Figure 1, in order that the pads may be disposed in the frame. At the forward end of the basket, which is open, is a 30 pair of horizontal feed rollers 13, journaled at their opposite ends in brackets 14, and between which the sheets of paper are to be fed. At one end, these rollers are equipped with intermeshing gears 15—15, one of 35 which is equipped with a thumb nut 16, whereby a rotation thereof will effect a rotation of the rollers in opposite directions, for obviously drawing the sheets of paper through the rollers, in order that the same 40 may pass into the basket. The nature of these sheets is such that when passing into the basket, they will again assume the folded condition as shown by dotted lines in Figure 1.

45 It will thus be seen that I have provided a highly novel and efficient form of paper

supply holder for typewriters, and one that will be well adapted for all of the purposes designated.

50 Minor changes may be made in the invention, without departing from the spirit and scope of the appended claims.

Having thus described my invention, what I claim as new and desire to secure by Letters Patent is:

55 1. In a paper supply holder for typewriters, a frame disposed rearwardly of the typewriter and being adapted to receive a multiplicity of folded sheet tablets, a typewriter platen, said sheets being adapted to 60 be fed to the typewriter platen, a pivoted basket upon the upper end of the frame, and means for feeding the paper into the basket.

2. In a paper supply holder for typewriters, a frame adapted to be supported 65 rearwardly of the typewriter, said frame being provided with individual paper holders, constructed to accommodate folded packets of different kinds of paper, the foremost holder being adapted to contain original paper, the rearmost holder being adapted to contain second sheets, and the intermediate holder to contain carbon paper, all 70 of said sheets being led from the open top of the holders to dispose them in superposed 75 relation, the superposed sheets being adapted to pass beneath the typewriter platen and upwardly over the same, and a basket supported from said frame and open at one end for reception of the superposed sheets. 80

3. In a paper supply holder for a typewriter, a frame comprising spaced vertical uprights provided with right angularly disposed attaching feet, upper and lower pairs of opposed bars extending rearwardly and 85 horizontally from said uprights, said bars being provided with paper holding and guiding means, and a paper receiving basket pivotally mounted upon the upper ends of 90 said uprights.

In testimony whereof I affix my signature.

ARTHUR A. MILLER.
